United States Patent Office

Des. 227,544
Patented July 3, 1973

227,544

CENTER SHEAR BLADE

Kunio A. Sumida, Los Angeles, Calif., assignor to
Leonard U. Shapiro, St. Paul, Minn.

Filed July 21, 1971, Ser. No. 164,978

Term of patent 14 years

Int. Cl. D8—99

U.S. Cl. D8—98

FIG. 1 is a perspective view of a center shear blade illustrating a new design therefor;

FIG. 2 is a top plan view thereof;

FIG. 3 is a side elevation view of the center shear blade taken from the side opposite FIG. 1;

FIG. 4 is a bottom plan view thereof; and

FIG. 5 is a front elevation thereof.

I claim:

The ornamental design for a center shear blade, substantially as shown.
